REGINALD ANDERSON, OF NORTH GRAFTON, MASSACHUSETTS, ASSIGNEE TO THE FOB-
BUSH SHOE COMPANY, OF NORTH GRAFTON, MASSACHUSETTS, A CORPORATION OF
MASSACHUSETTS

SHOE

Application filed May 31, 1929. Serial No. 367,405.

This invention relates to the upper of a shoe.

The principal objects of the invention are to provide a ventilated upper capable of being constructed in such a way as to have a pleasing appearance and having the same flexibility as an ordinary piece of leather of the same kind.

Other objects and advantages of the invention will appear hereinafter.

Reference is to be had to the accompanying drawings in which

Fig. 1 is a side view of a completed shoe constructed in accordance with this invention;

Fig. 2 is a plan of the upper, slit for receiving the cross pieces and cut out to shape;

Fig. 3 is a similar view showing the cross pieces introduced in the upper;

Fig. 4 is an edge of the same, and

Fig. 5 is a sectional view of the completed shoe taken at one side.

This shoe is manufactured in the same way as ordinary shoes except for the upper. The upper 10 consists of a piece of leather, elk or other material, ordinarily used for that purpose, cut out to the usual outline. It is provided with a separate tongue 11 and separate pieces 12 for the reception of the shoe lace if desired. These parts 11 and 12 preferably are made in a contrasting color to the upper 10. As for example, the upper may be made of a light tan color and the other parts of a dark brown.

The upper is provided with a series of slits 13 which extend all the way through it and radiate from practically a common center. They extend almost to the edge of the upper. It will be seen that the slits 13 divide up the toe of the upper into a series of strips 19, said strips starting along an arcuate line 20 just in front of the tongue 11 and extending substantially to the edges of the upper but not quite. Each of these strips is wider at its outer end than at its inner end.

Into these slits are inserted cross pieces 14, of leather or any desired material, contrasting in color, preferably, with the upper 10. In the present instance they are shown as

substantially of the same shades as the parts 11 and 12. It will be seen that they are threaded in over and under and around the arc of a circle across the top of the upper from the instep to the toe. The cross pieces 14 are in curved formation after being put in place, the curvature being controlled by the arc 20 at which the slits start. The ends of these cross pieces are trimmed off at the edge of the upper and the upper is used the same as is the case ordinarily and fastened into the rest of the shoe as shown in Fig. 5 or in any other ordinary way.

This produces a shoe which, except for the upper, is manufactured as usual but provided with a checker-board appearance on the top of the toe part. Ventilation is provided through the slits to render the shoe comfortable either for walking or for athletic purposes.

The ends of the cross pieces 14 are sewed to the upper by stitching 15 along the sides which secures the ends of all these cross pieces, except that those at the extreme rear end, which do not show in Fig. 1, are secured by the line of stitching 16 with which the counter 17 is secured to the upper. In this case it will be seen that this counter extends very far forward and does not extend clear to the top of the shoe as the upper extends back over the counter at 18 along the top of the shoe.

Although I have illustrated and described only one form of the invention I am aware of the fact that modifications can be made therein by any person skilled in the art without departing from the scope of the invention as expressed in the claim. Therefore, I do not wish to be limited in this respect but what I do claim is:—

As an article of manufacture, a shoe having an upper provided with slits radiating from an arcuate line in front of the tongue to the end and sides of the upper, so as to divide the upper into a series of strips integral with the upper at both ends and slightly wider at the outer ends than at said arc and cross pieces woven in and out among said strips from one side of the upper to the other, so

each one in curved form, whereby the top of the upper is given a checker-board appearance and a certain amount of ventilation is provided through said slits.

3 In testimony whereof I have hereunto affixed my signature.

REGINALD ANDERSON.
